(57) **CLAIM**

I claim the ornamental design for a roach clip with keychain, as shown and described.

DESCRIPTION

FIG. 1 is a front perspective view;

FIG. 2 is a front view;

FIG. 3 is a rear view;

FIG. 4 is a left side view;

FIG. 5 is a right side view;

FIG. 6 is a top view; and

FIG. 7 is a bottom view.

FIG. 8 is a side perspective view of the roach clip with keychain shown in an environment of use; and,

FIG. 9 is another perspective view of the roach clip with keychain shown in an environment of use.

The broken lines depicting a person and a set of keys detailed in FIGS. 8 and 9 show environment and form no part of the claimed design.

1 Claim, 6 Drawing Sheets
